vember 21, 1945, Serial No. 630,076

5 Claims. (Cl. 178—44)

1

This application is a division of parent U. S. application Number 459,457, filed September 24, 1942, and issued on April 11, 1950, as U. S. Patent 2,503,955.

The present invention relates to electrical circuits having characteristics similar to those of transmission lines.

An object of the present invention is the provision of an artificial line having uniformly distributed characteristics.

Another object of the present invention is the provision of an artificial line which is compact in size.

Still another object of the present invention is the provision of an artificial line having characteristics which do not vary with changes in the frequency of energy applied thereto.

A further object of the present invention is the provision of an artificial line which has a phase shift characteristic which is linear with respect to frequency.

Still a further object of the present invention is the provision of a compact artificial line which, in spite of its size, will handle large amounts of energy.

The foregoing objects, and others which may appear from the following detailed description, are attained in accordance with the principles of the present invention by so coiling or folding a natural line that it occupies a small space without at the same time introducing such mutual inductive effects, either electrostatic or electromagnetic, between different convolutions or layers of the coiled line that it ceases to act as a natural line.

The present invention will be more fully understood by reference to the following detailed description, which is accompanied by a drawing in which Figure 1 illustrates in vertical section an embodiment of the invention, while Figure 2 illustrates a transverse section of said embodiment.

Referring now to the drawing, the present invention utilizes a plurality of separate line sections 10 each of which may be supported within a shield 32. The sections may be connected in series and placed within a conductive container 34 which is filled with transformer oil. The container may be covered by an insulating top 35 which carries a terminal 36 to which one end of the line is connected, the other end being connected to the container 34 as indicated at 40. Each line section 10 is constructed by first winding the conductor 12 upon a small diameter mandrel to form an elongated helix, the successive turns of the helix being slightly spaced one

2

from the other. The helix, after being removed from the mandrel is then space wound upon an insulating support 31 which may be a glass tube or rod. The support 31 may be threaded to hold the turns in place or they may be cemented to the support by coating them with shellac or other cement. The shields 32 are preferably welded or soldered together into a honeycomb-like arrangement with combined spacing fins and supporting legs 38 attached to the periphery to maintain the desired relationship between the shields, the casing and the coils.

The turns of the original helix, being of such small diameter, have very little self-inductance, and their mutual inductance is also low while the field of each turn about support 31 is substantially confined to its own volume. Thus the total length of wire acts substantially as though it were stretched out at full length while still occupying a much more compact container.

While I have particularly shown and described a particular embodiment of the present invention, it should be clearly understood that the invention is not limited to this form alone, but that modifications may be made.

What is claimed is:

1. A compact artificial line including an elongated conductor, said elongated conductor being wound into a helix of small diameter, said helix being wound into a coil having an inner diameter substantially the same as the diameter of said helix, adjacent turns of said coil being spaced apart by a distance at which the field of each turn of said coil is confined to its own volume to prevent substantial decrease of mutual inductance, whereby the self inductance of the coil is substantially greater than that of said elongated conductor.

2. A compact artificial line including an elongated conductor, said elongated conductor being wound into a helix of small diameter, said helix being wound into a coil about a support having a diameter substantially the same as the diameter of said helix, the helix being insulated from said support, adjacent turns of said coil being spaced apart by a distance at which the field of each turn of said coil is confined to its own volume to prevent substantial decrease of mutual inductance, whereby the self inductance of the coil is substantially greater than that of said elongated conductor, and a tubular shielding member surrounding said coil.

3. A compact artificial line including a plurality of line assemblies each comprising an elongated conductor, said elongated conductor

being wound into a helix of small diameter, said helix being wound into a coil having an inner diameter substantially the same as the diameter of said helix, adjacent turns of said coil being spaced apart by a distance at which the field of each turn of said coil is confined to its own volume to prevent substantial decrease of mutual inductance, whereby the self inductance of the coil is substantially greater than that of said elongated conductor, and a tubular shielding member surrounding said coil, said assemblies having the elongated conductors thereof connected in series and the shielding members thereof connected to a point of zero reference potential.

4. A compact artificial line including a plurality of line assemblies, each comprising an elongated conductor, said elongated conductor being wound into a helix of small diameter, said helix being wound into a coil having an inner diameter substantially the same as the diameter of said helix, adjacent turns of said coil being spaced apart by a distance at which the field of each turn of said coil is confined to its own volume to prevent substantial decrease of mutual inductance, whereby the self inductance of the coil is substantially greater than that of said elongated conductor, and a tubular shielding member surrounding said coil, said assemblies having the elongated conductors thereof connected in series and the shielding members thereof connected to a point of zero reference potential.

5. A compact artificial line including a plurality of line assemblies each comprising an elongated conductor, said elongated conductor being wound into a helix of small diameter, said helix being wound into a coil having an inner diameter substantially the same as the diameter of said helix, adjacent turns of said coil being spaced apart by a distance at which the field of each turn of said coil is confined to its own volume to prevent substantial decrease of mutual inductance, whereby the self inductance of the coil is substantially greater than that of said elongated conductor, and a tubular shielding member surrounding said coil, said assemblies having the elongated conductors thereof connected in series and the shielding members thereof connected to a point of zero reference potential, said assemblies being immersed in an insulating fluid.
